UNITED STATES PATENT OFFICE.

AUGUST H. REHNER, OF NORWOOD, OHIO.

MULTIPLE-SPINDLE DRILL-HEAD.

1,079,023.

Specification of Letters Patent. Patented Nov. 18, 1913.

Application filed March 19, 1913. Serial No. 755,899.

To all whom it may concern:

Be it known that I, AUGUST H. REHNER, a citizen of the United States, residing at Norwood, in the county of Hamilton and State of Ohio, have invented certain new and useful Improvements in Multiple-Spindle Drill-Heads, of which the following is a specification.

My invention relates to multiple spindle drill-heads, applicable in machines for drilling, boring and reaming metal, and performing similar operations, and it has for its object the provision of novel means whereby the distance between the spindles is readily changed; further in the provision of novel means for mounting an adjustable spindle in a head of the character stated; further in novel means for securing the adjustable parts in adjusted positions; further, in novel means for mounting the spindles and the driving means between the same; further, in novel means for mounting the head; and the invention will be further readily understood from the following description and claims, and from the drawings, in which latter:

Figure 1 represents a side elevation of my improved device applied to a drilling machine of ordinary type, so much of the drilling machine being shown as is necessary to illustrate my invention. Fig. 2 is an axial section of my improved device taken on the line 2-2 of Fig. 3. Fig. 3 is a bottom view of my improved device. Fig. 4 is a transverse section of my improved device taken on a line corresponding to the line 4-4 of Fig. 2. Fig. 5 is a detail in cross-section on a line corresponding to the line 5-5 of Fig. 2, showing the means for clamping the head in radially adjusted positions. Fig. 6 is a detail in cross-section on a line corresponding to the line 6-6 of Fig. 2, showing the means for clamping the axially movable spindle in adjusted positions and for limiting its axial movements. Fig. 7 is a detail in section on the line 2-2 of Fig. 3 showing the clamping means for the plates of the movable spindle in unclamped relation; and, Fig. 8 is a detail in section on a line corresponding to the line 8-8 of Fig. 3, showing the means of mounting the intermediate gear between the plates.

I illustrate and describe my invention

as an attachment to an ordinary drilling machine, but it is obvious that the same may be employed as a permanent part of the machine.

11 represents the frame of a usual drilling machine having a usual drill-arm 12 in which there is a bearing 13.

14 represents a usual mandrel for receiving the usual drill, this mandrel being rotatable in a sleeve 15, which is slideable up and down in the bearing 13. The mandrel is held longitudinally in the sleeve and moves up and down with the sleeve. The longitudinal movement of the sleeve may be accomplished by a rack 16 on the sleeve with which a pinion 17 co-operates, the pinion 17 being on a shaft 18 rotatable in the drill-arm and operable by an ordinary handle 19. The drill-mandrel may be rotated in suitable manner by usual power driving mechanism or otherwise. The drill-mandrel is provided with an ordinary taper-socket 20 for receiving the usual drill.

26 represents the casing of my improved device in which there is a bearing 27.

28 is an arbor which rotates in this bearing, a bushing 29 being shown interposed between the arbor and the bearing. A pair of gears 30, 31, are on the arbor and there is a journal 32 adjacent its lower end. This arbor has rotation imparted to it in suitable manner exemplified by its connection with the drill-mandrel.

36, 37, are a pair of plates. The plate 36 has an opening 38 through which the arbor extends. The plate 37 has a bearing 39 shown as a bushing in which the journal 32 rotates. A collar 40 is received about the lower end of the arbor, this lower end being screw-threaded, as shown at 41, for receiving a nut 42. The lower end is reduced in diameter for forming a shoulder 43 against which the collar is clamped.

The drill spindles of my improved device are shown at 46, 47. Means are provided for adjusting the distance between these spindles and also for relative lengthwise adjustment between the same. The drill-spindle 46 is shown as adjustable toward and from the drill-spindle 47 for adjusting the distance between them, and the drill-spindle 46 is shown as adjustable axially for relative lengthwise adjustment between the drills. The drill-spindle 46 is shown as re-

latable in bearings 48, 49, exemplified as bushing in the plates 36, 37. An end-thrust bearing 50 is provided for this drill-spindle exemplified as a collar 51 bearing against the plate 37 and nuts 52, 53, screwed about the threaded lower end 54 of the spindle. Balls 55 are received in runways between the collar 51 and the nut 52. The spindle 46 is provided with a gear 56.

10 The spindle 46 is provided with a taper-socket 57 for receiving the drill 58. For removing the drill there is a hole 59 in the casing with which a hole 60 in the upper end of the spindle may be caused to register, the holes being arranged to receive a suitable knock-out pin against the end of the drill. The hole in the casing is arranged to be closed by a cap 61 swinging on a pin 62. An intermediate gear 65 rotates on studs 66 in bearings 67, shown as bushings located in the plates 36, 37. The gear 65 is meshed by the gear 31 and in turn meshes with the gear 56 on the drill-spindle 46 for turning the latter. The gears 65, 31, move with the spindle 46 in the lateral adjustment of the latter, and in the form shown there is a simultaneous movement of the plates 36, 37, with said gears and spindle when said spindle is adjusted.

20 The drill spindle 47 is journaled in bearings 70, 71, exemplified as bushings, and 72 is an end-thrust bearing therefor. The end-thrust bearing 72 is shown as comprising plates 73, 74, provided with runways in which balls 75 are received, a shoulder 76 on the spindle bearing against the plate 74. The spindle is held in upward relation by means of a nut 77 and a jam-nut 78, threaded about the upper threaded end 79 of the spindle, a collar 80 being interposed between the nut 77 and the bushing 70. The spindle 47 has a gear 83 thereon shown as an elongated gear. A gear 84 is meshed by the gear 30 on the arbor and meshes with the gear 83 and rotates on a stud 85 secured to the casing, the stud having a flange 86 received in a recess in the gear 84. The spindle 47 has a taper-socket 89 in which a drill 90 is received. The spindle is provided with a slot 91 and the wall of the casing is provided with a slot 92. A suitable drift pin may be forced through these slots against the end of the drill for releasing the drill.

30 The bushing 70 is arranged to be clamped in place in a clamp-bearing 95, shown as a split-bearing, having a clamp-bolt 96 between the ears 97, 98, of said split-bearing, for clamping said ears toward each other and thereby clamping the bushing. In order to avoid axial adjustment of the spindle 47 beyond limits which insure proper meshing between the gears 83, 84, I provide the bushing with a slot 99 in which a limiting screw 100 in the clamp-bearing 95 is received. If it is desired to axially adjust

the spindle 47, the split-bearing thereof is loosened and the spindle adjusted to proper axial position, and the bearing again tightened for clamping the bushing in place in adjusted position.

70 For locating the plates 36, 37, I prefer to provide substantially annular rabbets in which said respective plates are received. The peripheral walls 101, 102, of these recesses locate the plates centrally with relation to the arbor 28. The wall 101 is interrupted at 103 to permit proper meshing between the gears 83, 84.

75 The bases of the recesses preferably form shoulders 104, 105, which may be annular shoulders. The plates 36, 37, are arranged to be forced toward the shoulders for locating said plates and rigidly connecting the same with the casing of my improved device after adjustment of the laterally movable 85 spindle.

80 The bases of the recesses preferably form shoulders 104, 105, which may be annular shoulders. The plates 36, 37, are arranged to be forced toward the shoulders for locating said plates and rigidly connecting the same with the casing of my improved device after adjustment of the laterally movable 85 spindle.

85 For securing the parts in place I prefer to provide the plates with peripheral grooves 108, 109, shown as tapered in cross-section, in which correspondingly tapered 90 shoes 110, 111, are received, the shoes being clamped by means of screws 112, 113, having conical ends 114, 115, received in conical recesses. The axes of said conical ends of the screws are normally non-incident to the 95 axes of said respective conical recesses.

90 Forcing the screws inwardly will force the tapered ends of the screws against that side of the tapered recesses in the shoes nearest the shoulders, for forcing the said shoes and plates toward said shoulders, and thereby clamping the plates in adjusted positions by agencies which exert great clamping force with little exertion. The screws are shown as provided with knurled heads 100 for clamping and unclamping the parts without the use of tools.

95 I have shown the driving connection between the arbor of my improved device in the present exemplification as consisting of a plug 121 shown tapered at both ends, the one end thereof being received in the usual taper-socket 20 of the drill-mandrel of the machine and the other end thereof received in a taper-socket 123 of the arbor 28. The 110 upper end of the wall of the socket 123 may be provided with a recess 124 for receiving a pin 125 in the spindle. A hole 126 may extend through the arbor for receiving a knock-out pin for knocking out the plug 120 from the taper-socket in the arbor.

115 The end-thrust bearing 127 may be provided between the casing and the arbor, shown accomplished by a collar 128 received about the upper end of the arbor in 125 which the arbor rotates, and a nut 129 screwed about the upper threaded end 130 of the arbor, a jam-nut 131 clamping the nut 129, the collar 128 and nut 129 having anti-friction balls 132 therebetween for 130

forming a ball bearing. The collar 126 is arranged to be contained by the bushing.

If desired, means may be provided for clamping the casing to the longitudinally movable sleeve of the machine, shown accomplished by a clamp-sleeve 126, having an upper clamp-bearing 127 arranged to be clamped about the longitudinally movable sleeve of the drill and a lower clamp-bearing 128 arranged to be clamped about the bearing 27 of the casing. This clamp-sleeve is shown as a split-sleeve, the clamping about the longitudinally movable sleeve being effected by the bolt 139 between the ears 140, 141. The clamp about the casing may comprise a bolt 142 between the ears 143, 144, of the casing and may further comprise shoes 145, received in an annular slot 146 in the bearing 27. The shoes are arranged to be clamped about the bearing by means of clamp-screws 147, the finer ends whereof are received in recesses 148, in said shoes for permitting release of said clamp-screws to a considerable extent without 25 drawing the same from said shoes, whereby the dropping of the head from the clamp-sleeve is prevented. If it is desired to effect adjustment of the casing about the axis of the drill-shaft, the clamp-screws 147 are 30 slightly withdrawn which is readily accomplished by manually turning the knurled heads of said screws, when the casing may be swung about the axis of the drill-shaft for locating the drill in proper position. 35 to the work upon the best of the machine, whereupon the shoes may again be clamped in place for rigidly securing the parts together. I provide means for readily releasing the plug from the drill-shaft, which is accomplished by means of a drift-pin received through suitable slots 149 in the clamp-sleeve and the usual slot 150 in the drill-shaft.

The drill-spindle 46 may be swung about the axis of the arbor 38 for adjusting it laterally with relation to the drill-spindle 47. In the drawings the drill-spindles are shown at their positions of greatest separation. When brought to points of closest approach, 45 the drill-spindle 46 is closely adjusted to the drill-spindle 47, being received under the gear 84, which drives the drill-spindle 47. The trains of gearing for the respective drill-spindles are located in different planes 50 extending at right angles to the arbor for the purpose.

There is an index gage between the plate 37 and the casing, consisting of the index-mark 152 on the edge of the casing, and the 55 index-numerals 153 on the plate 37. The plate 37 serves as a closing plate for the mouth of the casing, the casing being of bell-like form enclosing the gearing for driving the drill-spindles.

Having thus fully described my invention, what I claim as new and desire to secure by Letters Patent, is:

1. In a multiple spindle drill-head, the combination of an arbor, a pair of drill-spindles, an axially adjustable sleeve in 70 which one of said drill-spindles is positioned lengthwise, means whereby the axial adjustment of said sleeve is effected whereby the lengthwise relation between said drill-spindles is adjusted, means between said arbor 75 and said drill-spindles for rotating said drill-spindles, and means whereby the lateral distance between said drill-spindles is adjusted.

2. In a multiple spindle drill-head, the combination of a frame, an arbor journaled therein, a gear on said arbor, a pair of plates adjustable about the axis of said arbor, a drill-spindle, a bearing therefor in each of said plates, a gear about said drill-spindle 85 having operative connection with said first-named gear, and a second drill-spindle journaled in said frame, said first-named drill-spindle, plates and second-named gear simultaneously shiftable about the axis of said 90 arbor for moving said first-named drill-spindle toward and from said second-named drill-spindle.

3. In a multiple spindle drill-head, the combination of a bell-like casing, an arbor 95 journaled in said casing, a pair of plates about said arbor in said casing, a drill-spindle journaled in said plates, a gear on said drill-spindle between said plates, a gear between said plates and on said arbor with 100 which said last-named gear has operative connection, and a second drill-spindle journaled in said casing outside said plates, said first-named drill-spindle, plates and first-named gear simultaneously shiftable about 105 the axis of said arbor for moving said first-named drill-spindle toward and from said second-named drill-spindle.

4. In a multiple spindle drill-head, the combination of a casing having a plurality of substantially similar recesses of different diameters therein, a plurality of plates of different diameters received in said recesses, an arbor about which said plates are rotatable, a spindle journaled in said plates and movable therewith about said arbor, driving means between said arbor and spindle, and clamping means between said casing and plates for clamping said respective plates in 110 said recesses.

5. In a multiple spindle drill-head, the combination of a bell-like casing, an arbor journaled therein, a closing plate at the mouth of said bell-like casing, a drill-spindle journaled in said plate, a drill-spindle 115 journaled in said casing, and trains of gearing in different planes parallel to said plate between said arbor and said respective drill-spindles.

spindles, said trains of gearing located in the hollow of said bell-like casing closed by said plate.

6. In a multiple spindle drill-head, the combination of a bell-like casing, an arbor journaled therein, a closing plate at the mouth of said bell-like casing, a drill-spindle journaled in said plate, a drill-spindle journaled in said casing, and trains of gearing 10 in different planes parallel to said plate between said arbor and said respective drill-spindles, said trains of gearing located in the hollow of said bell-like casing closed by said plate, said train of gearing between said 15 arbor and second-named drill-spindle comprising an elongated gear on said second-named drill-spindle, and means for the adjustment axially of said second-named drill-spindle and elongated gear.
- 20 7. In a multiple spindle drill-head, the combination of a bell-like casing having a plurality of substantially annular shoulders, a pair of plates respectively co-operating with said shoulders, an arbor central with relation 25 to said shoulders, a drill-spindle journaled in said plates, a drill-spindle journaled in said casing, said plates rotatable about said arbor for adjusting the distance between said drill-spindles, and wedge-clamps acting 30 on said plates for clamping said plates toward said shoulders and permitting retraction of said plates from said shoulders.

8. In a multiple spindle drill-head, the combination with the longitudinally shiftable sleeve and the drill mandrel rotatable therein, of a casing, a clamp sleeve, said clamp sleeve having a clamp-bearing at one end thereof about said longitudinally shiftable sleeve and a bearing at the other end 35 thereof about said casing, said casing provided with an annular groove, clamp-shoes in said groove, and clamping screws in said last-named bearing extending substantially into said shoes whereby said casing is suspended from said sleeve during clamped or unclamped relation of said shoes.

9. In a multiple spindle drill-head, the combination of a bell-like casing, a plate for closing the mouth of said casing, an arbor 50 journaled in said casing, a drill-spindle projecting through said plate, a second drill-spindle journaled in said casing, driving means between said arbor and said drill-spindles, and means for adjustment of said first-named drill-spindle and plate about the axis of said arbor for adjusting said first-named drill-spindle toward and from said second-named drill-spindle.

10. In a multiple spindle drill-head, the combination of a casing, a pair of plates 55 therein, an arbor, a drill-spindle journaled in said plates, a gear on said arbor, a gear on said drill-spindle, an intermediate gear having journal support in said plates and meshing with said gear on said arbor and with

said gear on said drill-spindle, said three gears located between said plates, a drill-spindle journaled in said casing, a second gear on said arbor, an intermediate gear journaled on said casing and meshing with said last-named gears on said last-named drill-spindle and arbor, said last-named three gears located outside said plates, and said plates with said first-named drill-spindle and said gear thereon and said first-named intermediate gear adjustable about the axis of said arbor for adjusting the distance between said drill-spindles. 70

11. In a multiple spindle drill-head, the combination of a casing provided with a pair of shoulders, a pair of plates in said casing arranged to coact with said shoulders, an arbor in said casing, a drill-spindle journaled in said plates, a gear on said arbor, a gear on said drill-spindle, an intermediate gear having journal support in said plates and meshing with said gear on said arbor and with said gear on said drill-spindle, said three gears located between said plates, a drill-spindle journaled in said casing, a second gear on said arbor, an intermediate gear journaled on said casing and meshing with said last-named gears on said last-named drill-spindle and arbor, said last-named three gears located outside said plates, and 85 said plates with said first-named drill-spindle and said gear thereon and said first-named intermediate gear adjustable about the axis of said arbor for adjusting the distance between said drill-spindles. 90

12. In a multiple spindle drill-head, the combination of a casing, a pair of plates in

said casing, an arbor in said casing, a drill-spindle journaled in said plates, a gear on said arbor, a gear on said drill-spindle, an intermediate gear having journal support in said plates and meshing with said gear on said arbor and with said gear on said drill-spindle, said three gears located between said plates, a drill-spindle journaled in said casing and having longitudinal movement therein for lengthwise adjustment between said drill-spindles, a second gear 105 on said arbor, an intermediate gear journaled on said casing and meshing with said last-named gears on said last-named drill-spindle and arbor, said last-named three gears located outside said plates, and said plates with said first-named drill-spindle and said gear thereon and said first-named intermediate gear adjustable about the axis of said arbor for adjusting the distance between said drill-spindles. 110

13. In a multiple spindle drill-head, the combination of an open-ended casing provided with a shoulder, an arbor, a plate rotatable about said arbor, a drill-spindle extending through said plate, said plate pro- 115

vided with a peripheral groove having a radially inclined upper wall, a clamp-shoe in said groove, said clamp-shoe provided with a tapering recess, and a clamp-screw 5 in said casing having a conical end co-operating with the wall of said recess for clamping said plate against said shoulder.

14. In a multiple spindle drill-head, the combination of an open-ended casing provided with concentric annular guides of different diameters, a pair of plates guided by said respective guides, the larger of said plates forming a closing plate for said casing, an arbor central with relation to said 15 plates, a drill-spindle journaled in said plates, a gear thereon between said plates, a gear on said arbor with which said last-named gear has operative connection, a drill-spindle journaled in said casing outside said 20 annular guides, a gear on said arbor, an intermediate gear meshing therewith, a gear on said last-named spindle, the smaller one of said guides being interrupted for permitting meshing of said intermediate gear 25 and said last-named gear, said plates rota-

table in said guides for adjusting the spindle journaled therein toward and from said last-named spindle, and arranged for moving said last-named spindle under said intermediate gear, and means for clamping said plates rigid to said casing. 30

15. In a multiple spindle drill head, the combination of a bell-like casing, an arbor journaled therein, a gear on said arbor, a plate, said plate journaled in said casing and 35 said arbor having a journal in said plate, a drill-spindle journaled in said plate, a gear on said spindle having operative connection with said first-named gear, a drill-spindle, and gearing between said arbor and said second-named drill-spindle, and said plate rotatable about said spindle for adjusting the lateral distance between said drill-spindles. 40

In testimony whereof, I have hereunto signed my name in the presence of two subscribing witnesses.

AUGUST H. REHER.
